HAROLD C. BAKER AND OSCAR A. BOSS, OF NEW YORK, N. Y.

CLEANING DEVICE FOR RADIO TUNING DIALS

Application filed August 7, 1930. Serial No. 473,684.

This invention refers to cleaning devices and more particularly to that class of cleaning devices adapted to clean the vernier face of radio receiving set dial members thereby producing more efficient radio receiving sets.

One object of this invention is to produce a cleaning device in combination with a radio receiving set whereby any dust or foreign matter settling on the vernier face of tuning dials may be automatically cleaned therefrom as said dial is rotated during the tuning of said sets.

Another object is to furnish a cleaning device for radio dials of radio receiving sets wherein the cleaning member arranged to sweep the vernier dial face thereof is rotated in a direction opposite to the rotation of the dial whereby extraordinary sweeping action is obtained.

Another object is to furnish a cleaning device for tuning dials of radio receiving sets wherein the vernier dial face of said dials is automatically cleaned of dust and other foreign matter as said dial is ordinarily rotated for tuning the sets.

Another object is to furnish a cleaning device for tuning dials of radio receiving sets wherein the portion of the vernier dial face being advanced into the escutcheon or viewing opening therefor will be cleaned before moving to said opening irrespective of the direction of rotation of said dial during the tuning of a set.

Another object is to furnish a cleaning device for tuning dials of radio receiving sets which may be secured to the escutcheon member or cabinet portion independently of the removable chassis.

Another object is to furnish a cleaning device for tuning dials of radio receiving sets wherein the vernier dial face portion of said dials being advanced into view before a viewing opening of said sets will be cleaned before being so advanced into view, said cleaning device however being concealed from normal view during said cleaning operation.

Another object is to furnish a cleaning device for tuning dials of radio receiving sets wherein the pressure of the cleaning member bearing on the vernier dial face of said dials

will be balanced substantially equally over the entire face of said dials.

Other objects and advantages will appear as the description of the invention progresses and the novel features thereof are pointed out in the appended claims.

This invention consists in the novel construction and arrangement of parts hereinafter described, delineated in the accompanying drawings and particularly pointed out in that portion of this instrument wherein patentable novelty is claimed for certain and peculiar features of the device it being understood that, within the scope of what hereinafter thus is claimed, divers changes in the form, proportions, size and minor details may be made without departing from the spirit of, or sacrificing any of the details of the invention.

In describing the invention in detail, reference is had to the accompanying drawings, wherein is illustrated embodiments of the invention, and, wherein like characters of reference refer to corresponding parts throughout the several views, and in which:—

Figure 1 is a part sectional view through a radio receiving set of conventional form to which our improved form of cleaning device has been applied, and Fig. 2 is a part sectional, part plan view of the same taken on line 2—2 of Fig. 1, and Fig. 3 is a part elevational view of the same taken on line 3—3 of Fig. 1, and Fig. 4 is another part elevational view of the same taken on line 4—4 of Fig. 1, and Fig. 5 is a detailed enlarged sectional view of a portion of said device, and Fig. 6 is a sectional view of the same taken on line 6—6 of Fig. 5, and Fig. 7 is a plan view of a developed detail of said device, and Fig. 8 is a part sectional view of a radio receiving set to which a modified form of our invention has been applied, and Fig. 9 is a part elevational view of the same taken on line 9—9 of Fig. 8, and Fig. 10 is a developed detail part of said modified form of device, and Fig. 11 is a part sectional view of a radio receiving set showing still another modified form of cleaning device, and Fig. 12 is a perspective view of a cleaning member therefor, and Fig. 13 is an elevational view of a modi-

fied method of supporting the brush supporting member shown in Figs. 3 and 4, and Fig. 14 is an elevational view of a detailed part thereof taken on line 14—14 of Fig. 13 and 5 Fig. 15 is a part sectional view of a radio receiving set showing still another modified form of tuning dial cleaning device, and Figs. 16 and 17 are fragmental detailed views of a modified portion thereof.

10 Referring to Figs. 1, 2, 3, 4, 5, 6, and 7, the radio receiving set 1 is of conventional form comprising cabinet portion 2, having opening 3, arranged to receive escutcheon or viewing member 4 having rear viewing opening 5, positioned adjacent vernier dial face 6 of dial member 7 forming a part of chassis 8 arranged to be moved toward and away from said rear opening 5 and guided by rails 8a, said dial face 6 being illuminated by lamp 9, whereby the radio broadcasting stations indicated by the vernier reading thereon may be positioned relatively to the indicator 4a.

15 Cleaning device 10, comprises stationary hinge portion 11 secured to the upper face 12 of escutcheon member 4, said hinge portion being arranged to receive pin 13 for pivotally supporting brush supporting member 14 comprising bracket 15 formed from stamping 16, said bracket having hinge portions 17—17, bridge portion 18, and bearing portions 19—19 arranged to rotatably support brush members 20—20 comprising bristles 21 woven between wires 22—22 having bearing caps 23 and 24 secured at each end thereof, cap 23 supporting friction roller 25 and cap 24 friction roller 26. Spring 27 supported by hinge pin 13 is normally arranged to restrain brush supporting member 14 away from opening 5 whereby brush members 20—20 are arranged 20 to frictionally engage the vernier face 6 of dial 7.

25 The operation of cleaning device 10 is as follows:—When chassis 8 is removed from cabinet 2, the lower end of brush supporting member 14 is restrained to the right away from opening 5 by action of spring 27. When said chassis is returned to said cabinet and is moved to the left in rails 8a, friction roller 25 first engages dial member 7 where- 30 after further movement to the left of said chassis will finally restrain the peripheral edge of said dial to engage friction roller 26 and whereafter said chassis cannot be moved further to the left owing to the direct thrust 35 against hinge pin 13. Said chassis is locked in position in known manner whereafter any movement of dial 7 will act to frictionally rotate rollers 25 and 26 whereupon brush members 20—20 are rotated, the difference in contact diameter between said brush members and friction rollers, as well as the spiral formation of said brush members, acting to produce a sweeping action on the vernier face 6 in this manner cleaning all dust or foreign 40 matter therefrom.

45 Referring to Figs. 8, 9 and 10, the modified form of cleaning device 30 is adapted for use in radio receiving sets having a dial member as 31 formed with a cylindrical vernier face as 32 and driving tracks as 32a—32a on either side thereof. Said modified form of cleaning device comprises bracket member 33 secured to cabinet portion 2, said bracket being shown in developed form as member 34, (Fig. 10), said bracket member having base portion 70 35 and arms 36—36 arranged to rotatably support shaft 37 having friction rollers 38—38 and gears 39—39 secured thereto, also to rotatably support shaft 40 having brush 41 and pinions 42—42 secured thereto, said pinions meshing with said gears and driven 75 thereby.

80 Dial member 31 assumed to be supported by a chassis also assumed to be guided by rails as 8a in relation to cabinet portion 2, is 85 formed with tracks as 32a—32a preferably out of view of the opening 5, said tracks normally engaging friction rollers 38—38 whereby rotation of said dial member will restrain rotation of said rollers in this manner 90 causing gears 39—39 to rotate pinions 42—42 and brush member 41 in reverse direction to the rotation of said dial member whereby an extraordinary sweeping action is obtained between said brush member and the vernier 95 surface 32 of said dial member. It is to be noted that when said chassis is removed said cleaning device 30 remains as a fixed portion of cabinet 2, further, as said chassis is returned to said cabinet and is moved to the 100 left in rails 8a, the brush member 41 first contacts with vernier face 32, whereafter further movement acts to cause friction rollers 38—38 to engage the tracks 32a—32a in this manner establishing an initial pressure of 105 said brush member against said vernier face.

110 Referring to Figs. 11 and 12 showing still another modified form of cleaning devices 50—50, said devices comprise spring clamp members 51 having channels 52 arranged to receive felt pads or cleaning members 53, the spring clip portions 54 acting to resiliently adjustably clamp said pads in position in said channels. Said devices 50—50 are preferably rigidly secured to escutcheon member 4 in a manner hereinafter described.

115 When the radio receiving set includes a chassis having a bevel face type of dial member as 7, one each of said cleaning devices 50 is secured to each side portion 55 of escutcheon member 4 and said cleaning pads 53 are formed with a bevel edge as shown by the full lines of Fig. 12. However when said chassis includes a dial member having a cylindrical 120 formed vernier face as 32, a rectangular form 125 of pad 53 as shown by the dotted lines of Fig. 12, is employed and said cleaning devices are secured to the top and bottom portions 12 and 12a of said escutcheon member.

130 Referring to Figs. 13 and 14 showing still

another modified form of cleaning device 60, said device being a modification of the device shown in Figs. 1 to 7 inclusive, said device comprises a brush supporting member 61 similar to member 14 however, having hinge portions 17-17 omitted and being further modified by the addition of stud members 62-62 having stop portions 63-63 allocated by orifice 64a in bracket portions 64-64 formed on bracket member 65 secured to cabinet 2, springs 66-66 acting to restrain said brush member 61 in the direction of vernier face 6 of dial member 7. The operation of cleaning device 60 is substantially the same as that of device 10.

Referring to Fig. 15, showing still another modified form of cleaning device 70 for tuning dials of radio receiving sets, said device comprises bearing member 71 secured to cabinet 2, said member rotatably supporting shaft 72 having operating handle 73 secured to one end thereof and cleaning brush member 74 secured to the other end thereof, said brush member comprising disk portion 75 formed integrally with conical portion 76 having orifices 77-77 supporting brush bristles 78-78, said conical portion having a cut-away portion 79 to normally permit viewing dial face 6 through opening 5. Cleaning brush member 74 is formed with eye portion 80 arranged to engage one end of tension spring 81 having the other end thereof secured to stud 82 supported by cabinet 2. Spring 83 supported by shaft 72 is normally arranged to restrain handle 73 and cleaning brush member 74 to the left away from vernier face 6 of dial member 7.

The operation of cleaning device 70 is as follows:—The various brushes 78-78 substantially encircle the vernier face 6 of dial member but normally do not engage said surface. When it is desired to clean said vernier face the handle 73 is depressed inwardly or to the right, thereby compressing spring 83 and moving cleaning brush member 74 to the right whereby brushes 78-78 engage said vernier face except the viewed portion exposed to opening 5. After depressing said handles as described it is also rotated through an arc of a circle in each direction, said brush member passing through the opening, or space 5a, in this manner cleaning the entire vernier face at one time. When handle 73 is released said handle and brush member 74 moves to the left away from said vernier face and as said handle is free to rotate without restraint, spring 81 acts to center said brush member whereby the cut-away portion 79 registers with said viewing opening 5.

Referring to Figs. 16 and 17, showing a modified form of cleaning member 90 for substitution for the cleaning member 74 of Fig. 15, dial member comprises the disk portion 91 supported by shaft 72, said disk portion 91 having an attachment portion or rim 91a ar-

ranged to support felt pads, or cleaning projections 92-92 having the opening 79-79 formed therebetween said pads being secured by rivets 93-93. The modified form of cleaning member 90 has the advantage that it may be employed for cleaning the vernier faces of tuning dial having said faces at varying angles thereon, said pads being flexible and therefore capable of accommodating itself to various angles of inclination thereof. It has the further advantage that any one of the openings as 79 may be employed to register with the view opening 5 when said cleaning member is not in use.

It is to be understood that the cleaning members as 74 and 90 are arranged to have the cleaning portions thereof pass through the passageway 5a between the escutcheon 4 and the vernier face 6 of dial member 7.

What we claim is:—

1. The combination with a radio receiving set comprising a housing having a chassis positioned therein, the housing having a viewing opening formed therein and the chassis including a tuning dial member having a dial face indicating radio broadcasting stations formed thereon positioned to be viewed through the opening for selectively tuning in the set during the movement of the dial member, of means positioned within the housing arranged to frictionally engage the dial member for effecting cleaning of the dial face thereof whereby the face will appear as dust free as it is moved before the viewing opening during the movement of the dial member. 100

2. The combination with a radio receiving set comprising a housing having a chassis positioned therein, the housing having a viewing opening formed therein and the chassis including a tuning dial member having a dial face indicating radio broadcasting stations formed thereon positioned to be viewed through the opening for selectively tuning in the set during the movement of the dial member, of a cleaning device associated with the set, and a cleaning member supported thereby arranged to frictionally engage the dial member for effecting cleaning of the dial face whereby the face will appear dust free as it is moved before the viewing opening 115 during the movement of the dial member.

3. The combination with a radio receiving set comprising a housing having a chassis positioned therein, the housing having a viewing opening formed therein and the chassis including a tuning dial member having a dial face indicating radio broadcasting stations formed thereon positioned to be viewed through the opening for selectively tuning in the set during the movement of the dial member, of a cleaning device comprising, a frictional member positioned to engage the dial member and be actuated thereby as the dial is moved, and means actuated by the friction member arranged to frictionally engage the 130

dial face of the dial member for removing the dust therefrom upon actuation of the friction member by the movement of the dial member.

- 5 4. The combination with a radio receiving set comprising a housing having a chassis positioned therein, the housing having a viewing opening formed therein and the chassis including a tuning dial member having a dial face indicating radio broadcasting stations formed thereon positioned to be viewed through the opening for selectively tuning in the set during the movement of the dial member, of means positioned within the housing arranged to resiliently frictionally engage the dial member for effecting the cleaning of the dial face thereof whereby the face will appear as dust free as it is moved before the opening during the movement of the dial member.
